(57) **CLAIM**

The ornamental design for an industrial mixer, as shown and described.

DESCRIPTION

The patent or application file contains at least one drawing executed in color. Copies of this patent or patent application publication with color drawing(s) will be provided by the Office upon request and payment of the necessary fee.

1. Industrial mixer

2. Industrial mixer

1 is a front view of a first embodiment of an industrial mixer showing my new design.

2 is a front view of a second embodiment of an industrial mixer showing my new design.

The industrial mixer consists of a protruding operating and management element which is the claimed part and an area for the attachment of non-claimed test assemblies which is the unclaimed part; the lines in red are only for illustrating the boundary between the claimed part and the unclaimed part and form no part of the claimed designs.
